UNITED STATES PATENT OFFICE.

CYPRIEN CHABOT, OF PHILADELPHIA, PENNSYLVANIA.

MACHINE FOR CHANNELING SOLES.

SPECIFICATION forming part of Letters Patent No. 280,576, dated July 3, 1883.

Application filed January 24, 1881. Renewed March 6, 1882. Again renewed November 27, 1882. (No model.)

To all whom it may concern:

Be it known that I, CYPRIEN CHABOT, a citizen of the United States, residing in Philadelphia, Pennsylvania, have invented certain Improvements in Machines for Channeling or Slitting Shoe-Soles, of which the following is a specification.

My invention relates to certain improvements in that class of machines which are employed for cutting channels or thread-slots in the sole-blanks of boots and shoes, the objects of my invention being to effect the automatic guiding of the sole as it is fed through the machine, to properly regulate the depth of the thread-slot cut in the sole, and to so construct the knife for cutting the thread-slot that said knife will be strong and durable and capable of being readily sharpened.

In the accompanying drawings, Figure 1 is a longitudinal vertical section of sufficient of the machine to illustrate my improvements, the machine being adapted for cutting the thread-slot in the sole; Fig. 2, a front view of the machine; Fig. 3, the same with the knife-slide and its bearings removed and with the work-table and gearing detached; Fig. 4, a plan view of part of Fig. 2; Figs. 5 to 9, detached views of parts of the machine; Figs. 10, 11, and 12, views illustrating the cutting-knives and the character of the work performed thereby; Fig. 13, Sheet 2, a diagram illustrating the operation of the feeding devices; and Figs. 14 to 19, inclusive, views illustrating the construction of the slot-cutting knife.

A is the main frame of the machine, which forms part of a column or standard, A', and has bearings for a shaft, B, the front end of which carries a bevel-wheel, a, the projecting rear end of the shaft being furnished with pinions b and d and an operating crank or handle, e. The bevel-wheel a gears into a pinion, a', forming part of a sleeve, f, the latter turning on a pin, f', which projects from a lug on the frame A, and is inclined, as shown in Fig. 1.

Secured to the upper end of the sleeve f is a disk, g, the upper face of which is made conical.

A frame, D, is pivoted at its rear end to the frame A, the front end of said frame D being

under the control of a spring, E, and a lever, F. The spring E tends to depress the frame D, and the tension of said spring is regulated by the adjustment of a set-screw, h. One arm of the lever F bears on the frame D, and the other arm of said lever is connected by means of a link, h'; and rod h² to a treadle suitably located, whereby the front end of the frame D can be elevated when desired.

To bearings in the frame D is adapted a tubular shaft, G, the front end of which carries a serrated feed-wheel, m, a spur-wheel, b', being carried by the rear end of said shaft and gearing into the pinion b. The pinion d gears into a spur-wheel, d', secured to the projecting rear end of a shaft, H, which is adapted to the hollow shaft G and projects from the front end of the same, the projecting end of the shaft being provided with a serrated feed-wheel, n, similar to the wheel m of the shaft G. The pinions b d and spur-wheels b' d' are so proportioned that the speed at which the surface of the feed-wheel m travels will be somewhat greater than the surface speed of the wheel n. The spur-wheel b' can, however, turn independently of the shaft G under the circumstances described hereinafter, said spur-wheel being composed of three rings, c, c', and c², Fig. 9, the central ring, c, being keyed to the shaft and adapted to recesses in the outer rings, c' and c². The ring c' has external teeth adapted to those of the pinion b, and is provided with an internal thread adapted to the threaded periphery of the ring c², so that by screwing up or unscrewing said ring c² the degree of friction may be readily governed. Washers, of felt, leather, gum, or equivalent material, are by preference interposed between the ring c and the rings c' and c², so as to afford a good frictional surface.

A gage-plate, i, is located in respect to the disk g as shown in Figs. 1, 5, and 6, the frame A being slotted for the passage of the confining screw or bolt, whereby the gage-plate is held, so that said plate can be adjusted in respect to the feed-wheels.

The machine shown in the drawings is designed for cutting the thread-slot in a shoe-sole, as shown in Fig. 12, M being the cutting-knife, which is carried by a slide, N, adapted

to suitable vertical guides in the front end of the frame A. The slide N is recessed for the reception of a plate, P, Figs. 1, 3, and 7, which is secured to the slide by means of a bolt, s, passing through a vertical slot in the slide, the plate P being hung to a lever, S, one end of which is slotted for the reception of a pivot-pin, t, on the frame A, the opposite end of the lever being adapted to a slot in a bar, W, which is free to reciprocate vertically in guides in the frame A. When in use the lower end of the bar W rests upon the shoe-sole, and is maintained in contact with the same by the action of a spring, w, upon the plate P, the tension of this spring being regulated by an appropriate set-screw. When the frame D and the feed-wheels *m* and *n* are elevated or depressed, the bar W and knife M are likewise elevated or depressed, owing to the contact of the projecting end of the shaft H with arms on the bar W. (See Figs. 3 and 7.) The arm has, however, a slight play independent of the feed-wheels. The slide N can be adjusted vertically in respect to the plate P by manipulating a set-screw, y, which is adapted to a threaded opening in the slide, and has an annular groove for the reception of a lug on the plate P. (See Fig. 7.)

In preparing the machine for work the knife M is so set in respect to the bar W that when the latter bears upon the top of the shoe-sole the point of the knife will penetrate to the proper extent beneath the surface of the same. The frame D is elevated, the shoe-sole introduced into its place on the disk *g*, with the edge of the sole bearing against the gage-plate *i*, and the frame D is then allowed to descend, so that the sole is clamped between the feed-wheels *m* *n* and the disk *g*. The feed-wheels being then rotated, the sole is fed forward, the knife M penetrating the sole to the extent permitted by the bar W, and thereby cutting the thread-slot in said sole. As the surface of the feed-wheel *m* moves at a somewhat higher rate of speed than the surface of the feed-wheel *n*, there is a constant tendency of the edge of the sole to move in the direction of the arrow, Figs. 6 and 13, so that said edge is kept firmly pressed against the gage-plate *i* without any attention or manipulation on the part of the operator, the guidance of the sole as it is fed through the machine being thus rendered automatic. The curved surface of the sole, however, constantly varies in radius, as will be observed on reference to Fig. 13, Sheet 2, so that while a portion of short radius—such as the heel or toe—is being fed to the knives the point *x* must travel at a higher rate of speed in respect to the point *x'* than when the side of the sole or other part of greater radius is being acted upon, the two points *x* *x'* in this case moving at almost the same speed; hence, if the surface speed of the wheel *m* is so much in excess of that of the wheel *n* as to effect the proper pressure of the sole-edge against the gage *i* while acting on the heel or toe portion of the sole, the excess

of speed would be too great when the wheels are acting on a portion of greater radius, and there would be a tendency of the wheels to cut or tear the surface of the sole. For this reason I use the friction-clutching device before described for connecting the spur-wheel *b'* to the hollow shaft *G*, which carries the feed-wheel *m*, so that as soon as there is any undue resistance to the feeding action of the wheel *m* the spur-wheel *b'* will slip and the movement of the wheel *m* will be retarded, the feeding action of said wheel being thus accommodated to the portion of the sole which is being acted upon. As the thickness of the sole varies, a vertical movement is imparted to the presser-bar W, and this movement is transmitted through the medium of the lever S to the plate P and knife-carrying slide N, the movement of the said slide being always less than the movement of the bar, owing to the fact that the plate P is connected to the lever S at a point closer to the fulcrum of said lever than the connection of the bar W.

In order that the point of connection of the plate P and lever S may be varied, I provide the plate and lever with several pairs of holes, to either of which the connecting-pin may be adapted. By this means the depth of the thread-slot is always proportionate to the thickness of the sole. For instance, if the knife M is set so as to cut a slot an eighth of an inch deep when the lower end of the bar W is bearing upon a portion of the sole one-quarter of an inch thick, an increase in the thickness of the sole to one-half of an inch would cause the bar to rise one-quarter of an inch, the knife M rising to a somewhat less extent, owing to the connections above described, so that the depth of the slot in the half-inch portion of the sole would be one-eighth of an inch plus the difference between the extent of rise of the bar W and that of the knife-slide.

The cutting-knife M, Figs. 10 and 11, is peculiarly constructed, and forms one of the features of my invention, for, although it consists of a straight bar of steel, the cutting portion is so formed that the slot cut in the sole is partly horizontal and partly inclined, this result being attained by so beveling the back of the knife that when the latter is held in an inclined position in the machine the cutting portion at the point will be horizontal, as shown in Fig. 10. The mode of making the knife will be understood on reference to Figs. 14 to 19, Sheet 2, Figs. 14, 15, and 16 representing, respectively, a perspective view, edge view, and back view of the knife before being beveled, and Figs. 17, 18, and 19 being corresponding views of the finished knife. The end of the bar M is first sharpened, as shown in Figs. 14 to 16, so as to present a straight cutting-edge, *v*; but if the knife so constructed were held in the inclined position shown in Fig. 15, an inclined slot only would be cut in the sole. Hence I bevel the point of the knife from the back, as shown in Figs. 17 to 19, so that when

the knife is held in the inclined position shown in Fig. 18 the cutting-edge v' of the beveled portion of the knife will be horizontal, and will cause a corresponding shape to be imparted to the bottom of the slot cut in the sole by the knife. By this means I am enabled to cut in the sole a slot possessing all the advantages of the usual curved slot without the necessity of using a curved knife, which is fragile and difficult to sharpen.

It will be evident that the knife M, constructed as above described, can be made as strong as desired, and can be readily sharpened on an ordinary grindstone without the exercise of special care or skill.

The differential feed-wheels m n may be used in connection with a knife or knives for cutting a channel in the edge of the sole, as well as with the knife M, and the slide carrying the latter knife can be operated in a manner different from that shown without departing from the main feature of this part of my invention. For instance, the plate P may in some cases be dispensed with and the slide N connected directly to the lever S, and the said lever S may be operated from the projecting end of the shaft H, instead of by a bar, W. The use of said bar is preferred, however, as its lower end will not sink into soft or spongy leather to such an extent as the serrated feed-wheels m n .

I claim as my invention—

1. The combination, in a shoe-sole channeling or slotting machine, of a work-supporting disk or bed, a gage for the edge of the sole, a cutting knife or knives, and two feed-wheels, one of which has a higher surface speed than the other, and both adapted to act upon the same surface of the sole, whereby the edge of the sole is automatically held in contact with the gage, as set forth.

2. The combination, in a shoe-sole channeling or slotting machine, of a work-supporting disk or bed, a gage for the edge of the sole, a cutting knife or knives, and two feed-wheels, m and n , the wheel n having a definite rotating movement and the wheel m being dependent for its rotation upon a frictional driving device, all substantially as specified.

3. The combination of a work-supporting disk or bed, feeding devices, a knife-carrying slide, N, a presser-bar or equivalent device resting on the sole, and a lever interposed between the said bar and the knife-slide, whereby the depth of the slot cut by the knife is varied to accord with the thickness of the sole, as set forth.

4. The combination of the work-supporting and feeding devices, the presser-bar W, or its equivalent, the lever S, the plate P, connected thereto, and the knife-carrying slide N, secured to said plate P, so as to be adjustable vertically thereon, as set forth.

5. The combination of the knife-carrying slide N and its grooved set-screw y with the plate P, having a lug adapted to the groove of said set-screw, as set forth.

6. The combination of the work supporting and feeding devices, the movable frame D, carrying said feeding devices, the knife-carrying slide N, the presser-bar W, moving with the frame D, but capable of a limited vertical movement independently thereof, and the lever S, interposed between said presser-bar and the knife-slide, as set forth.

7. The slot-cutting knife M, consisting of a straight bar of steel sharpened at the end to form the cutting-edge v' , and beveled at the back, whereby when the knife is held in the machine at an angle the cutting-edge v' of the point or beveled portion of the knife will occupy a horizontal position and the slot cut by the knife will be partly horizontal and partly inclined, as set forth.

8. In a sole-channeling machine, the combination of the feed-wheel shaft G with the spur-wheel b' , composed of the tapered ring c , clamping-rings c' and c'' , and intervening washers, as set forth.

In testimony whereof I have signed my name to this specification in the presence of two subscribing witnesses.

CYPRIEN CHABOT.
